DESIGN FOR A COMBINATION SUPPORT AND SNUFFER FOR CIGARETTES

Iigo Kornbluh, Brooklyn, N. Y., assignor to Alex Katz, New York, N. Y.

Application July 1, 1940, Serial No. 93,371

Term of patent 3½ years

To all whom it may concern:

Be it known that I, Iigo Kornbluh, a citizen of Germany, a resident of Brooklyn, in the county of Kings, city and State of New York, have invented a new, original, and ornamental Design for a Combination Support and Snuffer for Cigarettes, of which the following is a specification, reference being had to the accompanying drawing, forming part thereof.

port and snuffer for cigarettes showing my new design.

I claim:

The ornamental design for a combination support and snuffer for cigarettes, substantially as shown.

IGHO KORNBLUH.
